[57] CLAIM

The ornamental design for a femoral cutting jig for the
implantation of a prosthetic knee, substantially as
shown and described.

DESCRIPTION

FIG. 1 is a top plan view of a femoral cutting jig for the
implantation of a prosthetic knee of my new design;
FIG. 2 is a front elevation view of the femoral cutting
jig shown in FIG. 1;

FIG. 3 is a rear elevation view of the femoral cutting jig
shown in FIGS. 1-2;

FIG. 4 is a bottom plan view of the femoral cutting jig
shown in FIGS. 1-3;

FIG. 5 is a side elevation view of the femoral cutting jig
shown in FIGS. 1-4; and

FIG. 6 is a cross-sectional view taken through FIG. 1
along the line 6—6.
